ATTORNEY'S

UNITED STATES PATENT OFFICE

115,228

DESIGN FOR A COMBINED HAT AND SCARF

Alfred Cohn, Milwaukee, Wis.

Application September 10, 1938, Serial No. 79,830

Term of patent 14 years

To whom it may concern:

Be it known that I, Alfred Cohn, a citizen of the United States, residing at Milwaukee, in the county of Milwaukee and State of Wisconsin, have invented a new, original, and ornamental Design for a Combined Hat and Scarf, of which the following is a specification, reference being had to the accompanying drawing, forming part thereof.

In the drawing:

Figure 2 is a three-quarter rear view of a combined hat and scarf embodying my design.

I claim:

The ornamental design for a combined hat and scarf, as shown.

ALFRED COHN.
